UNITED STATES PATENT OFFICE.

EDWARD HALE DICKIE, OF GOLDRoad, ARIZONA.

CARBURETER.

Specification of Letters Patent. Patented Mar. 28, 1916.

1,177,395.

Application filed December 29, 1914. Serial No. 879,547.

To all whom it may concern:

Be it known that I, EDWARD H. DICKIE, a citizen of the United States, residing at Goldroad, in the county of Mohave and State of Arizona, have invented certain new and useful Improvements in Carbureters; and I do hereby declare the following to be a full, clear, and exact description of the invention, such as will enable others skilled in the art to which it appertains to make and use the same.

This invention has for its object to provide a carbureter of improved and simplified construction embodying a sprayer nozzle having an enlargement adapted to coöperate with the wall of the mixing chamber to control the flow of air thereto.

Another object is the provision of a carbureter embodying a vertically movable sprayer nozzle carrying a hollow stem extending into a fuel reservoir and adapted to coöperate with a stationary plug or valve arranged in the reservoir to control the flow of fluid through the stem.

With these and other objects in view, the invention consists in the novel construction, arrangement and formation of parts as will be hereinafter specifically described, claimed and illustrated in the accompanying drawings, in which the figure represents a vertical sectional view through the carbureter, partly broken away.

Referring to the drawing in detail, the numeral 5 indicates the hollow body of the carbureter forming the mixing chamber 6 supporting the constant level fuel reservoir 8. The constant level reservoir 8 is connected with the fuel reservoir 18 by a suitable fuel pipe 19 and the reservoir 18 is formed integral with the lower part 20 of the body of the carbureter, which is threaded at its upper end 21 into the lower open end of the upper body part 5. The part 20 is formed above the reservoir 18 with a plurality of openings 22, and the upper portion 20 of the lower part is separated from the reservoir 18 by a partition 23 having a central aperture 24. The lower end of the reservoir 18 is formed with a threaded opening 25 receiving a plug 26 having a reduced and tapered upper end 27 constituting a valve, as will be hereinafter described.

The hollow stem 28 of a nozzle 29 is slidably mounted through the aperture 24 and a suitable packing ring 30 is threaded upon an upstanding flange 31 carried by the par-

tition 23 to prevent the escape of fuel between the stem 28 and the wall of the opening 24. The bore or passage 33 through the stem 28 and nozzle 29 communicates with the mixing chamber 6 and the fuel reservoir 18, and the nozzle 29 is formed with a hollow substantially conical enlargement 34 adapted to coöperate with the seat 35 formed in the lower end of the upper part 5 to control the flow of air from the lower part 20 to the mixing chamber 6. The stem 28 carries a pair of diametrically opposed pins 36 slidably received within the bifurcated ends of a lever 37 pivotally supported at 38 on the lower body part 20. The upper end of the upper part 5 is connected with an elbow 39 adapted to be connected with the intake or intake manifold of a gas engine and is preferably provided with a throttle valve 40 operable by a throttle lever (not shown). The upper body part 5 is provided with a lateral enlargement 42 adjacent the extension 7 and formed with a circular bore 43 receiving a rotary valve 44 having an angular port 45 therethrough. The bore 43 of the enlargement communicates with the mixing chamber 6 through a passage 46, and the outer portion of the wall of the bore 42 is formed with an air port 47. The rotary valve 44 is operable by a lever 48 secured to a concentric extension 49 carried by said valve.

In use, liquid fuel is conducted from the bowl 8 to the reservoir 18 through a fuel pipe (not shown) and enters the mixing chamber 6 through the passage 33 in the stem 28 and nozzle 29. The quantity of air entering the chamber 6 for mixture with the fuel sprayed from the nozzle 29 may be varied by adjusting the lever 37 which moves the nozzle 29 and enlargement 34 thereof relative to the seat 35 and thus increases or decreases the space between these elements. In starting an internal combustion engine, as is well known, it is desirable to prime the same by introducing fuel directly to the cylinders thereof, and this may be accomplished with my carbureter by adjusting the nozzle 29 so as to nearly close the lower end of the body part 5 and permit fuel and only a small quantity of air to enter the elbow 39 and cylinders (not shown) through the passage 33. When it is desired to cut off the flow of fuel, the free end of the lever 37 is swung upwardly thus lowering the stem 28 and nozzle 29 and en-

gaging the lower end of the stem upon the tapered upper extremity 27 of the plug 26, thus closing the passage 33 and preventing the flow of fuel through the stem. When the 5 stem 28 is in its lowermost position and the bore or passage 33 thereof is closed by the tapered extremity 27 of the plug 26 the enlargement 34 is spaced a considerable distance from its seat 35, thus admitting an 10 increase in the quantity of air admitted to the engine. The valve 44 is designed for admitting an additional air supply during the operation of the motor and is commonly known as an auxiliary air valve.

15 What I claim is:

1. A carbureter comprising upper and lower parts, said upper part having a mixing chamber and the lower part having air inlets therein, a fuel reservoir carried by the 20 lower part, a nozzle movable in said mixing chamber, a stem carried by said nozzle extending into said reservoir and having a longitudinal passage therethrough, and means arranged in said fuel reservoir adapted to be engaged by said stem to close the passage 25 through the latter.

2. A carbureter comprising upper and lower parts, said upper part having a mixing chamber and the lower part having air 30 inlet openings therein, a fuel reservoir formed integral with the lower part and separated from the latter by an apertured partition; a nozzle movably mounted in the upper part, a stem projecting through said 35 apertured partition and having a longitudinal passage therethrough, and a plug arranged in said fuel reservoir adapted to engage in said passage to close the latter.

3. A carbureter comprising a hollow body 40 having a mixing chamber in the upper portion and a plurality of air inlet openings in the lower portion thereof, a fuel reservoir formed integral with the lower portion of said body, an apertured partition separating said fuel reservoir from said body, a nozzle movably mounted in said mixing chamber and having a substantially conical enlargement adapted to coöperate with the wall of said mixing chamber to control 45 the flow of air from said inlet openings to said mixing chamber, a hollow stem carried by said nozzle communicating the latter with said reservoir, means for adjusting said nozzle, and means arranged in said fuel 50

reservoir adapted to engage within the lower 55 extremity of the bore of the hollow stem to close the latter.

4. A carbureter comprising a hollow body having a mixing chamber in the upper portion thereof and a plurality of air inlet openings in the lower portion thereof, a fuel reservoir carried by the lower portion of said body having an aperture in the lower end thereof, a plug removably positioned in the lower end of said reservoir and having a tapered extension projecting inwardly of said reservoir, a nozzle movably mounted in said mixing chamber having a substantially conical enlargement adapted to coöperate with the wall of said mixing chamber 70 to control the flow of air from said air inlet openings to said mixing chamber, a hollow stem formed integral with said nozzle and communicating the latter with said fuel reservoir, the lower end of the bore of 75 said hollow stem being flared and adapted to coöperate with the tapered extension of said plug to control the flow of fuel to said mixing chamber, and means for adjusting said nozzle.

5. A carbureter comprising upper and lower parts, said upper part having a mixing chamber therein and an aperture in the wall of said mixing chamber, a valve communicating with said aperture, said lower 85 part having a plurality of air intake openings therein, a nozzle movably mounted in the upper portion of said body and having a substantially conical enlargement adapted to coöperate with the wall of said mixing 90 chamber to control the flow of air from said air inlet openings to said mixing chamber, a hollow integral extension carried by said nozzle and projecting downwardly therefrom, a fuel reservoir in the lower portion of said body receiving the lower extremity of said hollow extension, a valve in said reservoir adapted to coöperate with the lower extremity of said hollow stem to control the flow of fuel therethrough, and means 100 for adjusting said nozzle vertically.

In testimony whereof I affix my signature in presence of two witnesses.

EDWARD HALE DICKIE.
